BOTTLE TURN-OVER DEVICE

Stephen A. Gurkey, Allentown, Pa., assignor to
Frank Vlossak and Charles Vlossak, trustees,
both of Palmerton, Pa.

Application November 3, 1934, Serial No. 751,409

10 Claims. (Cl. 259—72)

The invention relates to an improvement in means for mixing the contents of bottles, particularly soft drinks, during the course of which process the bottle is removed from an upright position on a carrier, turned on its side, then upside down, and then righted to normal position, for further processing or packing.

The details of my device are described as follows:

10. Figure 1 is a side elevational view of my machine, with the bottles traversing the machine from right to left.

15. Figure 2 is a side elevational view of the reverse side of my machine illustrated in Figure 1.

15. Figure 3 is a partial end elevational view of the bottle entrance to the machine, showing the means for placing the bottles in the machine.

20. Figure 4 is a sectional view on line 4—4 of Figure 9, showing the configuration of the track member on which the bottles travel from the entrance to the exit of the machine.

25. Figure 5 is a top plan view of the revolving bottle pusher arm illustrated in Figures 1, 2, and 3.

25. Figure 6 is a top plan view of the revolving arm means for moving the bottles over the first or primary section of the turn-over device to inverted position.

30. Figure 7 is a top plan view of the revolving finger gripping means for moving the bottles from their inverted position over the secondary section of the turn-over device to standing position at the exit of the machine.

35. Figure 8 is a partial top plan view of the revolving receiving table where the bottles are deposited by the machine, and the revolving accumulating table to which they are automatically transferred.

40. Figure 9 is a diagrammatic view showing the transverse positions assumed by the bottles during the course of their travel from the entrance to the exit of the machine.

45. Referring more specifically to the invention, the conveyor belt or chain 1 of conventional type is connected with the bottling or bottle capping machine, the bottles being placed in upright position on such belt by the bottling machine. The conveyor reverses its route of travel over pulley 2 (as shown in Figures 1, 2, and 3), the shaft of which is journaled into the end piece of the machine and bracket 3. The motive power for such conveyor is supplied by the mechanism of the bottling machine with which it is connected, or a stationary conveyor may be used and the

bottles pushed over its surface to the entrance of the turn-over device.

The bottles, upon nearing the entrance to the device are guided to the entrance by the guards 4—5, the former being placed at an angle across the conveyor in the manner shown in Figure 3.

As the bottle entering the machine reaches position opposite the entrance the revolving arm 6 pushes it over the edge of the conveyor which, being placed above the level of the flat section 10 of the track member, causes the bottle to tip and assume the horizontal position shown in Figure 9.

The means for operating the revolving pusher arm 6 are shown in Figures 1, 2, and 3. The 15 shaft 7 on the arm is journaled in the bracket 8, being revolved by means of the gears 9—10, shaft 11, gear 12, and connection by chains 13—14 and gear wheels 15, 16, 17, 18, with the motor 19, as shown in Figures 1 and 2.

The turn-over device proper comprises a dual railled track member consisting of a flat section 19, a primary arcuate section 20, and a secondary arcuate section 21. The surface configuration of the track member is shown in Figure 4, comprising two opposing rails, the track member being held firmly in position by being welded or otherwise secured to the side members 22—23 of the machine frame. The rails are spaced at a distance less than the diameter of the smallest bottles to be carried thereon.

At a point below the flat section 19 and primary arcuate section 20 of the track, the shaft 26 is journaled in the frame side members 24—25, the revolving arm 27 being keyed thereon between such side members and the rails of the track member.

The revolving arm 27 is illustrated in Figure 6, and comprises two spaced side members connected at either end by roller means.

The shaft 26 is connected with the motor as shown in Figures 1 and 2 and previously described, the arm 27 thus being revolved in the direction indicated between the side members 22, 23, 24, 25 of the frame and between the rails 45 comprising the flat section 19 and primary arcuate section 20 of the track member, each revolution describing an arc from the flat section through the arcuate section as illustrated in Figure 9.

As the revolving arm 27 reaches the bottle that has been deposited from the conveyor in horizontal position on the flat section 19, the roller forming the end of the arm member contacts the bottle and it is lifted to a position approximately 55

parallel to the arm member 27, the revolving movement of the arm pushing the bottle forward on the primary arcuate section 20 of the track. As the bottle moves forward it assumes the approximate positions shown in Figure 9 until, as the rotation of the arm 27 lowers its roller end below the level of the track, the bottle is shunted top downward into the V-shaped neck formed at the junction of the primary section 20 and secondary section 21 of the track.

The secondary section 21 of the track is of the same general surface configuration as that shown in Figure 4, and is similarly welded or otherwise fixed between the side members 22-23 of the machine frame.

A shaft 28 is journaled in the side members 22-23 on either side of the machine frame, being operatively connected with the motor by sprocket 29 and chain 30 with the sprocket 31 and shaft 26, as shown in Figure 2. The revolving double finger gripping means 32, illustrated in Figures 1, 2, 7, and 9, is keyed on shaft 28 between the side members of the frame, and between the double rails comprising the secondary arcuate section 21 of the turn-over track, revolving in the same direction as the arm 27.

As the finger gripping means 32 intercept the shoulders of the inverted bottle in the V between the primary and secondary arcuate sections of the track, the bottle is raised in the manner shown in Figure 9, being carried over the track section 21 and dropped against the buffer, or gate, member 33.

The gate member 33 is pivoted on either side in upright brackets 34-35 secured to each side of the machine frame, as shown in Figures 1, 2, and 8. The pivot allows its base to swing forward to a point where it almost impinges against the base of the track member 21, which is the terminus of the track, and prevents bottles from falling directly to the receiving table 36 as a means of preventing breakage. The buffer member is held in this position by the counterbalance weight 37 suspended on arm 38 and connected 45 with said buffer member.

As shown in Figure 1, near the base of buffer member 33 is secured the arm and roller member 39. This is further illustrated in Figure 8. The roller is held forward in position against the cam 50 wheel 40, which is keyed on the shaft 28 and revolves with the gripping means 32.

As shown in Figures 1 and 2 the surface configuration of the cam 40 is formed so that upon each half-revolution, after the gripping fingers 55 have delivered a bottle over the arcuate section 21 of the track to upright position with the bottom resting in the V formed by the base of the track and buffer member 33, the oscillating movement imparted to the roller resting against the cam surface forces the base of the buffer away from the track terminus and allows the bottle to drop slowly and places it free on the revolving receiving table 36.

As shown in Figures 1, 2, and 8, the receiving table 36 rests on an upright shaft 41 journaled in crosspiece 42 between brackets 43-44 secured to the frame of the machine.

The accumulating table 45, shown in the same figures, is level with the receiving table 36 and rests upon an upright shaft 46, similarly journaled in crosspiece 42 between the brackets 43-44 secured to the machine frame.

As shown in Figure 8, the base of each of the upright shafts 41, 46 is geared with the horizontal shaft 47, which is rotatively secured at both ends

to the bracket members 43, 44, and revolved by sprocket 48 and chain 49 connection with sprocket on shaft 29.

As the bottles are placed on the receiving table 36 by the movement of the buffer member 33, the revolution of such table places them between the guide members 50, 51 suspended by brackets 52, 53, from whence they proceed to the revolving accumulating table.

Having thus described my invention, I claim:

1. A bottle turn-over device of the character described, comprising a frame, a dual railed track mounted on said frame and comprising a primary and secondary section forming a V at the junction thereof, bottle pusher arm means rotatably mounted below the primary section of said track and the rotation thereof describing an arc intersecting said primary section and extending toward said V, bottle gripping means rotatably mounted below the secondary section of said track and the rotation thereof describing an arc from said V toward the terminus of said secondary section, and rotating means operatively connected with said bottle pusher arm and bottle gripping means.

2. A bottle turn-over device of the character described, comprising a frame, a bottle track mounted on said frame and comprising a primary and secondary section forming a V at the junction thereof, bottle pusher arm means rotatably mounted below the primary section of said track and the rotation thereof describing an arc intersecting said primary section and extending toward said V, bottle gripping means rotatably mounted below the secondary section of said track and the rotation thereof describing an arc from said V toward the terminus of said secondary section, and rotating means operatively connected with said bottle pusher arm and bottle gripping means.

3. A bottle turn-over device of the character described, comprising a frame, a dual railed track mounted on said frame and comprising a primary and secondary section forming a V at the junction thereof, bottle pusher arm means rotatably mounted intermediate the rails of said track and the rotation thereof describing an arc through said primary section toward said V, bottle gripping means rotatably mounted intermediate the rails of said track and the rotation thereof describing an arc from said V toward the terminus of said secondary section, and rotating means operatively connected with said bottle pusher arm and bottle gripping means.

4. A bottle turn-over device of the character described, comprising a frame, a dual railed track mounted on said frame and comprising a primary and secondary section forming a V at the junction thereof, arm means rotatably mounted intermediate the rails of said track and comprising side members joined at the ends thereof, the rotation of said arm describing an arc through said primary section of said track toward said V, bottle gripping means rotatably mounted intermediate the rails of said track and the rotation thereof describing an arc from said V toward the terminus of said secondary section, and rotating means operatively connected with said arm and bottle gripping means.

5. A bottle turn-over device of the character described, comprising a frame, a dual railed track mounted on said frame and comprising a flat section with adjoining primary and secondary arcuate sections, means for placing bottles in horizontal position on said flat section, arm means rotatably mounted intermediate the rails of said

track and comprising side members joined by roller means at the ends thereof, the rotation of said arm describing an arc from said flat section through said primary arcuate section of said track, bottle gripping means rotatably mounted intermediate the rails of said track and the rotation thereof describing an arc from the junction of said primary and secondary arcuate sections of said track through said secondary arcuate section, and rotating means operatively connected with said arm and bottle gripping means.

6. A bottle turn-over device of the character described, comprising a frame, a dual railed track mounted on said frame and comprising a flat section with adjoining primary and secondary arcuate sections, means for placing bottles in horizontal position on said flat section, arm means rotatably mounted in said frame intermediate the rails of said track and comprising side members joined by roller means at the ends thereof, the rotation of said arm describing an arc from said flat section through said primary arcuate section of said track, bottle gripping means rotatably mounted in said frame intermediate the rails of said track and comprising 25 side members joined by roller means at the ends thereof, the rotation of said arm describing an arc from said flat section through said primary arcuate section of said track, bottle gripping means rotatably mounted in said frame intermediate the rails of said track and the rotation thereof describing an arc from the junction of said primary and secondary arcuate sections of said track through said secondary section, buffer means pivotally secured to said frame and normally in position with its base abutting the terminus of said track, rotatable cam means mounted on said frame and operatively connected with said buffer means, and rotating means operatively connected with said arm means, bottle gripping means, and cam means.

7. A bottle turn-over device of the character described, comprising a frame, a dual railed track mounted on said frame and comprising a flat section with adjoining primary and secondary arcuate sections, a bottle carrier member traversing the entrance to and at a higher level than said track, a bottle pusher arm rotatably mounted at the entrance to said track on a bracket secured to said frame, a revolving arm member intermediate the rails of said track and rotatably mounted on a shaft journaled in said frame below the flat and primary arcuate sections of said track, spaced parallel bottle gripping fingers intermediate the rails of said track and rotatably mounted on a shaft journaled in said frame below the secondary arcuate section of said track, a counterbalanced buffer member pivoted at the top portion thereof in a bracket secured to said frame and normally in position with its base inclined toward the terminus of said track, a cam member rotatably mounted on a shaft journaled in said frame, arm and roller means connecting said buffer member with said cam member, said cam member being shaped to swing said buffer member on its pivot away from the terminus of said track, receiving means fixed below the terminus of said track, and rotating means operatively connected with said pusher arm, revolving arm, gripping finger, and cam members.

8. A bottle turn-over device of the character described, comprising a frame, spaced parallel side members on said frame, a dual railed track mounted on said side members and comprising a flat section with adjoining primary and secondary arcuate sections, a bottle carrier member traversing the entrance to and at a higher level than said track, a bottle pusher arm rotatably mounted at the entrance to said track on a bracket secured to said frame, a revolving arm member intermediate the rails of said track and side members of

said frame and rotatably mounted on a shaft journaled in said side members below the flat and primary arcuate sections of said track, spaced parallel bottle gripping fingers intermediate the rails of said track and side members of said frame and rotatably mounted on a shaft journaled in said side members below the secondary arcuate section of said track, a counterbalanced buffer member pivoted at the top portion thereof in a bracket secured to said frame and normally in position with its base inclined toward the terminus of said track, a cam member rotatably mounted on a shaft journaled in said side members below the secondary arcuate section of said track, a counterbalanced buffer member pivoted at the top portion thereof in a bracket secured to said frame and normally in position with its base inclined toward the terminus of said track, a cam member being shaped to swing said buffer member on its pivot away from the terminus of said track, receiving means fixed below the terminus of said track, and rotating means operatively connected with said pusher arm, revolving arm, gripping finger, and cam members.

9. A bottle turn-over device of the character described, comprising a frame, spaced parallel side members on said frame, a dual railed track mounted on said side members the rails thereof being spaced at a distance less than the diameter of the bottles to be turned and comprising a flat section with adjoining primary and secondary arcuate sections, a bottle carrier member traversing the entrance to and at a higher level than said track, guide members forming a bottle passage to the entrance to said track, a bottle pusher arm rotatably mounted at the entrance to said track on a bracket secured to said frame, a revolving arm member intermediate the rails of said track and side members of said frame and rotatably mounted on a shaft journaled in said side members below the flat and primary arcuate sections of said track, said revolving arm being of sufficient length to extend above said primary arcuate section and comprising parallel spaced members joined at the ends thereof by roller means, spaced parallel bottle gripping fingers intermediate the rails of said track and side members of said frame and rotatably mounted on a shaft journaled in said side members below the secondary arcuate section of said track, said gripping means being of sufficient length to lift bottles from the space intermediate the primary and secondary arcuate sections of said track and to extend above said secondary section, a counterbalanced buffer member pivoted at the top portion thereof in a bracket secured to said frame and normally in position with its base inclined toward the terminus of said track, a cam member rotatably mounted on a shaft journaled in said frame, arm and roller means connecting said buffer member with said cam member, said cam member being shaped to swing said buffer member on its pivot away from the terminus of said track, receiving means fixed below the terminus of said track, and rotating means operatively connected with said pusher arm, revolving arm, gripping finger, and cam members.

10. A bottle turn-over device of the character described, comprising a frame, spaced parallel side members on said frame, a dual railed track mounted on said side members the rails thereof being spaced at a distance less than the diameter of the bottles to be turned and comprising a flat section with adjoining primary and secondary arcuate sections, a bottle carrier member traversing the entrance to and at a higher level than said track, guide members forming a bottle passage to the entrance to said track, a bottle pusher arm

rotatably mounted at the entrance to said track on a bracket secured to said frame, a revolving arm member intermediate the rails of said track and side members of said frame and rotatably mounted on a shaft journaled in said side members below the flat and primary arcuate sections of said track, said revolving arm being of sufficient length to extend above said primary arcuate section and comprising parallel spaced members joined at the ends thereof by roller means, spaced parallel bottle gripping fingers intermediate the rails of said track and side members of said frame and rotatably mounted on a shaft journaled in said side members below the secondary arcuate section of said track, said gripping means being of sufficient length to lift bottles from the space intermediate the primary and secondary arcuate sections of said track and to extend above said secondary section, a counterbalanced buffer member pivoted at the top

portion thereof in a bracket secured to said frame and normally in position with its base inclined toward the terminus of said track, a cam member rotatably mounted on a shaft journaled in said frame, arm and roller means connecting said buffer member with said cam member, said cam member being shaped to swing said buffer member on its pivot away from the terminus of said track, a receiving table fixed below the terminus of said track on a rotatable shaft mounted in a bracket secured to said frame, an accumulating table on a level with and adjoining said receiving table and fixed on a rotatable shaft mounted in a bracket secured to said frame, guide members forming a bottle passage from said receiving table to said accumulating table, and rotating means operatively connected with said pusher arm, revolving arm, gripping finger, cam, and table members.

STEPHEN A. GURKEY. 20
